HAIR WAVING DEVICE

Robert B. Seward, Guilford, Conn., assignor to
Zotos Corporation, New York, N. Y., a corpora-
tion of New York

Application November 30, 1932, Serial No. 644,961

1 Claim. (Cl. 132—36.2)

This invention relates to certain improve-
ments in hair waving devices in which a pre-
formed tress of hair is subjected to the action of
an exothermic material which, when moistened,
will of itself generate heat sufficient to impart
a so-called permanent wave to the tress.

My improved hair waving device comprises a
pad having an outer layer preferably of non-
absorbent material, as foil, parchment paper, or
10 the like and an inner layer of absorbent mate-
rial containing an exothermic material, such for
instance as calcium oxid, said inner layer being
in the form of an absorbent sheet impregnated
with the exothermic material.

15 Practical embodiments of my invention are
represented in the accompanying drawing, in
which the figure represents in perspective, one
form of my improved hair waving pad.

The outer layer 1 of my improved pad is
20 preferably made of any suitable non-absorbent
material, as foil, parchment paper, or the like.

Attached to the inner face of this outer layer
is an inner layer of absorbent material contain-
25 ing an exothermic material. In the figure this
inner layer is shown as a sheet 2 of absorbent
material which is impregnated with an exo-
thermic material, such for instance as calcium
oxid.

In practice, the tress of hair, not shown here-
in, may be wound in any well known or ap-
proved manner, the tress being moistened, either
before or after it is wound, with a suitable hair
waving solution.

5 The inner layer of the pad may then be mois-
tened with water or a hair waving solution, such
as that used for moistening the tress. The pad
is then wrapped around the wound tress in the
usual manner and the exothermic action starts
10 at once. Heat is then set up within the pad
sufficient to impart a so-called permanent wave
to the pre-formed tress without requiring appli-
cation of heat from an outside source.

15 It is evident that various changes may be re-
sorted to in the construction, form and arrange-
ment of the several parts without departing from
the spirit and scope of my invention, and hence
I do not intend to be limited to the particular
20 embodiments herein shown and described, but
what I claim is:

A hair waving pad comprising an outer layer of
non-absorbent material and an inner layer in the
25 form of a sheet of absorbent material impreg-
nated with an exothermic material.

ROBERT B. SEWARD.
